TORVAL N. ULEVOG, OF EARL GREY, SASKATCHEWAN, CANADA.

AUTOMOBILE-DOOR LATCH.

1,299,066.

Specification of Letters Patent. Patented Apr. 1, 1919.

Application filed September 30, 1918. Serial No. 256,314.

To all whom it may concern:

Be it known that I, TORVAL N. ULEVOG, a citizen of Canada, and a resident of Earl Grey, in the Province of Saskatchewan and Dominion of Canada, have invented certain new and useful Improvements in Automobile-Door Latches, of which the following is a specification.

The present invention relates to door latches, and more particularly to that type for application to the doors of motor vehicles and the like.

The object of this invention is to provide a latch of relatively few parts adapted to bind securely together for holding a door closed, and which when subjected to vibration, binds more tightly and effectively maintains the door closed under all conditions of movement of the vehicle.

The invention further aims at the provision of a latch embodying the above characteristics, and which is in general character similar to the form of latches used at the present time in vehicle body construction, and which may be easily operated to release the door, and which may be closed without the necessity of slamming the door.

The above, and various other objects and advantages of this invention will be in part described, and in part understood, from the following detailed description of the present preferred embodiment, the same being illustrated in the accompanying drawing, wherein:

Figure 1 is a fragmentary vertical section taken longitudinally through the upper part of a vehicle body door and the adjacent portion of the frame, illustrating an application of a latch constructed according to the present invention.

Fig. 2 is a horizontal section taken through the same substantially on the planes indicated by the line 2-2 in Fig. 1.

Fig. 3 is a detail fragmentary face view of the keeper, showing in section the position of the latch lever in engagement with the keeper.

Referring to the drawing A designates the body frame of a motor vehicle or the like and B a door mounted in the usual manner therein. Fitting in the door structure is a casing 10 open at one side and closed thereat by a removable plate 11. Pivotally mounted in the casing 10 on a pin 12 is a latch lever 13 the same projecting at one end through the outer edge of the casing

10 and movable in a slot 14 in said edge of the casing. The other end of the latch lever 13 has an enlargement or weight 15 adapted to normally urge the lever to turn 60 in one direction and maintain the lever substantially in a horizontal position.

The weighted end of the lever 13 is connected to one end of a frame 16 which is secured at its other end to the bottom of the 65 casing 10 and is adapted to assist the weight 15 in holding the outer or free end of the latch lever in raised position.

For manually swinging the free end of the latch lever down through the slot 14 a 70 handle or hand lever 17 is employed and may be in the form of a bail as shown having one end projecting through the inner side of the door and movable in an arcuate slot 18 and held in the slot by a head or 75 enlargement 19 formed upon the said end of the bail. The bail is spaced from the inner side of the door and is adapted to receive the finger thereabout for manually grasping the bail or lever 17 to turn the 80 same about its other end as an axis, the other end being relatively long to form a shaft 20 journaled in the casing 10 and plate 11 and having fixed thereon, and within the casing, a hub 21 to turn with 85 the shaft.

The hub 21 is provided with a radially extending arm 22 projecting substantially in a horizontal direction and having pivotal connection to the upper end of a link 23 90 which projects downward from the arm 22 and has pivotal engagement at its lower end with the weighted end of the latch lever 13. The arm 22 extends in the same 95 direction from the hub 21 as does the handle 17, and the latter is arranged over the weighted end of the latch lever 13. When the bail 17 is swung up it raises the link 23 and draws the weight 15 up against the tension of spring 16.

Coöperating with the latch lever 13 is a keeper 24 in the form of an L-shape casting fitted to the frame A opposite the free edge of the door B and having a slot or opening 25 into which the nose or free end of the latch lever 13 is adapted to project. The keeper 24 is provided with a downwardly and inwardly inclined guiding face 26 at its outer edge against which the latch is adapted to first engage, the face 26 guiding the latch to the lower end of a projection 27 depending in the slot 25 and having a flat

inner face 28 against which the latch lever is adapted to engage.

From the upper end of the projection 27 the keeper 24 is provided with an upwardly and inwardly inclined shoulder 29 against which the corresponding beveled upper edge of the latch lever 13 is adapted to engage. The spring 16 holds the latch in contact with the shoulder 29 and as the latter is inclined or beveled, the latch is retained under tension and from rattling at all times. The weight 15 and the spring 16 combine to settle or advance the free end of the latch lever 13 over the shoulder 29 and to thus insure the binding of the latch in position when the device is jarred or vibrated.

When the door is closed and latched, excessive pressure placed against the inside of the door may slide the latch lever 13 down the shoulder 29, but the latch lever is held from being released by the inner flat face 28 of the projection against which the latch lever binds. The projection 27 thus holds the latch lever positively from movement out of the keeper slot 25, and holds the door from becoming released. The guide 26 and shoulder 29 are formed upon the opposite edges of a block or rib integral with the body portion of the keeper 24 and which is extended down at the point of emergence of the inclined edges 26 and 29.

It is within the spirit of this invention to make such changes and modifications within the scope of the following claims, in the design and construction of the above described embodiment of the invention as will adapt the same to body construction of various types and to various other uses to which the latch may be put.

40. What is claimed is:

1. In a latch, the combination of a latch lever, means for normally urging the lever to swing in one direction for yieldingly holding the free end thereof in a raised position, and a keeper having a slot to receive the free end of the lever and provided in the outer portion of the slot with a downwardly and inwardly inclined guiding face terminating in a projection and having at the inner portion of the slot an upwardly inclined shoulder against which the latch lever is adapted to be yieldingly held and which terminates at its lower end in a vertical flat face to receive the latch lever thereagainst and retain the same from movement out of the slot.

2. In a latch, the combination of a latch lever, means for normally swinging the lever to raise the free end thereof, and a keeper having a slot for the reception of said

free end of the lever, the keeper having a depending projection in the slot with an inner flat face to retain the latch within the slot and having an inclined shoulder rising from said projection and against which said latch is adapted to yieldingly bind.

3. In a latch, the combination of a casing adapted to be inserted in a door, a latch lever pivoted in the casing, means connected to the latch lever for normally urging one end thereof upward and through the outer edge of the door, a hand lever mounted upon the door and having a portion projecting into the casing, a connection between the hand lever and the latch lever for depressing the raised end of the latter and retracting it within the door, and a keeper adapted to be secured to the door frame and having a slot to receive the free end of the latch lever when projected and having a guiding face to depress the lever and a wedge shaped shoulder inwardly of the guiding face against which the free end of the latch lever is adapted to bind when normally urged upward, said keeper also having a locking shoulder at the lower end of the wedge shaped portion to retain the latch lever in the keeper when the door is subjected to pressure from its inner side.

4. In a latch, the combination of a casing adapted to be inserted in a door, a latch lever pivoted in the casing, means connected to the latch lever for normally urging one end thereof upwardly and through the outer edge of the door, a hand lever mounted upon the door and having a portion projecting into the casing, a connection between the hand lever and the latch lever for depressing the raised end of the latter and retracting it within the door, and a keeper having a slot for the reception of said free end of the lever, the keeper having a depending projection in the slot with an inner flat face to retain the latch within the slot and having an inclined shoulder rising from said projection and against which said latch is adapted to yieldingly bind.

5. In a latch, the combination of a latch lever, means for normally swinging the lever to raise the free end thereof, and a keeper having a slot for the reception of the free end of the lever, said keeper having a depending projection in the slot with an inner flat face to retain the latch within the slot and having an inclined shoulder rising from said projection and against which said latch is adapted to yieldingly bind, the latter inclined face being adapted to retain the latch lever from vibration at all times.

TORVAL N. ULEVOG.
